UNITED STATES PATENT OFFICE.

WILLIAM Y. FORBES AND WILLIAM H. ROTHWELL, OF HUYTON, LIVERPOOL,
ENGLAND.

TYPE-WRITING MACHINE.

961,597.

Specification of Letters Patent. Patented June 14, 1910.

Application filed October 31, 1908. Serial No. 480,556.

To all whom it may concern:

Be it known that we, WILLIAM YUILE FORBES and WILLIAM HASTINGS ROTHWELL, both subjects of the King of Great Britain and Ireland, residing at "Lynwood," Huyton, Liverpool, England, have invented a new and useful Improvement in Type-Writing Machines, of which the following is a specification.

10 This invention has reference to typewriting machines, and relates to the formation or construction of the type arms of such machines.

15 In the annexed drawings Figure 1 is a front or face view of a type arm formed according to this invention. Fig. 2 is an elevation illustrative of the ordinary bell lever arrangement by which such type arms are actuated by the ordinary key levers.

20 Fig. 3 is a sectional plan of the bearings in which such type arms are pivoted. Fig. 4 is a plan and Fig. 5 is a side elevation, showing the general arrangement of a typewriting machine possessing type arms according to this invention.

25 It will be noted that the type arm illustrated, carries three types, namely, small letters, capitals, and figures, either of which is caused to print by shifting the position of the platen roller by means of shift keys.

30 The type arms 1 are similar in shape to two sides of a triangle, the type block 2 being attached thereto near the apex of the angle, while the arms are pivoted at their lower extremities or base of the triangle. The journals or pins 3 which form these pivots are coned at each end and lie in similarly coned sockets in the type arm frame 4. A single screwed stud 5, bearing upon the 35 middle or cylindrical portion of the pin 3,

between its coned ends, serves to centralize such pin 3 in its coned socket and thus maintain a true bearing. The axis of the pivot pins 3 forms in conjunction with the two limbs of the type arm a perfect triangle. 45 Consequently an extremely rigid construction of type arm is afforded, and any adjustment thereof must be effected at their pivot bearings. A bank of such pyramidal arms is arranged on each side of the machine, their 50 apexes resting upon a suitable saddle piece 6. Each type arm 1 possesses a cranked extension 7, which may be coupled in any suitable manner, as for example, by means of the rod 8, bell lever 9 and pull 10, with the 55 levers 11 of the type keys 12.

Having now described our invention, what we claim as new and desire to secure by Letters Patent is:—

1. In combination a V-shaped type arm, 60 aligned journals on the extremities of said arm, the axis of which journals forms, with the sides of the type arm, a substantially triangular figure, a type-block on the arm near the apex opposite the axis of the journals, and a lateral extension on one of said journals for actuating said arm; substantially as described.

2. In combination, a V-shaped type arm, double coned journals on each extremity of 70 said arm, a supporting frame having correspondingly coned recesses therein to receive said journals, and a stud for centering said journals in their sockets; substantially as described.

W. Y. FORBES.
W. H. ROTHWELL.
